UNITED STATES PATENT OFFICE.

FORREST J. SMITH, OF COPLEY, OHIO.

PLUG.

Application filed July 21, 1922. Serial No. 576,614.

To all whom it may concern:

Be it known that I, FORREST J. SMITH, a citizen of the United States, residing at Copley, in the county of Summit and State of Ohio, have invented new and useful Improvements in Plugs, of which the following is a specification.

This invention relates to improvements in spark plugs, the general object of the invention being to provide means for forming a double spark gap, thus increasing the effectiveness of the plug.

Another object of the invention is to provide means for magnetizing the member which provides the extra spark gap which facilitates the jumping of the current across the first gap.

This invention also consists in certain other features of construction and in the combination and arrangement of the several parts, to be hereinafter fully described, illustrated in the accompanying drawings and specifically pointed out in the appended claims.

In describing my invention in detail, reference will be had to the accompanying drawing wherein like characters denote like or corresponding parts throughout the several views, and in which:

Figure 1 is a longitudinal sectional view of one form of the invention.

Figure 2 is a side view of this form of the invention.

Figure 3 is a longitudinal sectional view of another form of the invention.

Figure 4 is a side view of this second form.

Referring to Figures 1 and 2, 1 indicates the shell of the plug, 2 the porcelain body and 3 the nut for holding the body in the shell. The electrode is shown at 4" and the ground wire at 5. In carrying out my invention I provide a third wire 6" which is embedded in the porcelain body and has its terminal located in the space between the end of the electrode and the end of the wire 5. Thus two spark gaps are formed so that two sparks are produced every time the circuit is completed to the plug. This will increase the efficiency of the plug and it will act to prevent the formation of carbon on

the points of the plugs. If one gap becomes fouled the other gap will fire and the force of the explosion will remove the carbon from the other gap.

The member 6" has its upper end connected with a bundle 8 of soft iron wire. The conductor 9 from the timer is provided with a coil 9' of insulated wire which surrounds the bundle 8 and is insulated therefrom and then the coil 9' is connected with the electrode 4". Thus the member 6" is magnetized which facilitates the passing of the current from the electrode to the terminal of this member.

Instead of embedding the bundle and coil directly in the body of porcelain I may place them in a sleeve 10 of porcelain and secure this sleeve to the upper part of the body as shown in Figures 3 and 4. This sleeve may be threaded to the body, as shown, or otherwise secured thereto.

It is thought from the foregoing description that the advantages and novel features of my invention will be readily apparent.

I desire it to be understood that I may make changes in the construction and in the combination and arrangement of the several parts, provided that such changes fall within the scope of the appended claims.

What I claim is:

1. A spark plug comprising a shell, an insulating body carried thereby, a ground wire carried by the shell, an electrode carried by the body, a coil connected with the electrode, a member carried by the body and having its terminal located between the end of the electrode and the ground wire and a soft metal core embedded in the body and connected with said member.

2. A device of the class described comprising a shell, an insulated body carried thereby, a ground wire carried by the shell, an electrode carried by the body, a member carried by the body and having its terminal located between the end of the electrode and the ground wire and means for magnetizing the said member from the ignition current.

In testimony whereof I affix my signature.

FORREST J. SMITH.
